UNITED STATES PATENT OFFICE.

BENNO VOM EIGEN, OF NEWARK, NEW JERSEY, ASSIGNOR TO AUG. GOERTZ & CO., OF NEWARK, NEW JERSEY, A FIRM.

BAG-FRAME.

No. 810,925.

Specification of Letters Patent.

Patented Jan. 30, 1906.

Application filed July 14, 1904. Serial No. 216,459.

To all whom it may concern:

Be it known that I, BENNO VOM EIGEN, a citizen of the United States, residing at Newark, in the county of Essex and State of New Jersey, have invented certain new and useful Improvements in Bag-Frames; and I do hereby declare the following to be a full, clear, and exact description of the invention, such as will enable others skilled in the art to 5 which it appertains to make and use the same, reference being had to the accompanying drawings, and to figures of reference marked thereon, which form a part of this specification.

15 This invention relates to improvements in bag-frames; and the invention has for its principal object to provide a bag-frame which is especially adapted for use with chatelaine or belt bags, but which may also be used for 20 other bags, the bag-frame comprising a pair of hinged or pivoted frame-sections, upon one of which is arranged a front cover-section, corresponding substantially to the 25 shape and configuration of the frame-section and serving the purposes of a cover or shield, behind which the rivet-heads of the rivets which are employed for securing the frame-section and its inlay to the mouth of the bag are arranged and are therefore not exposed 30 to view upon the front of the bag-frame.

A further object of this invention is to provide a novel bag-frame formed upon its front face with a rivet-head-concealing means, whereby a neat and unobstructed front face 35 of the bag-frame is the result.

A still further object of the present invention is to provide, in connection with a bag-frame comprising a pair of hinged or pivoted frame-sections, a front cover section or member which is separably and detachably connected with the frame-section, being preferably leather-covered and provided with any suitable construction of bag-frame fastener with which a holding-catch upon the oppositely-located frame-section of the bag-frame proper is adapted to be brought in holding engagement.

Other objects of the present invention not at this time more particularly specified will 50 be clearly evident from the following detailed description of the invention.

With the various objects of my invention in view the same consists in the novel bag-frame hereinafter set forth, provided upon

its front with a rivet-head-concealing means; 55 and, furthermore, this invention consists in the novel arrangements and combinations of the various devices and parts, as well as in the details of the construction of the same, all of which will be fully described and then 60 finally embodied in the clauses of the claim which are appended to and form an essential part of this specification.

The invention is clearly illustrated in the accompanying drawings, in which— 65

Figure 1 is a face view of a bag-frame embodying the principles of this invention. Fig. 2 is a rear or back view of the frame, and Figs. 3 and 4 are a top edge view and bottom view, respectively, of the bag-frame. Fig. 5 70 is a collective perspective view of the hinged frame-sections in their separated or open relation, one of the said frame-sections being represented as broken away and the separable front cover-section being shown detached 75 from the frame-section. Fig. 6 is a section taken on line 6-6 of Fig. 2. Fig. 7 is a detail transverse vertical section, on an enlarged scale, of the one frame-section and the front 80 cover-section, representing in connection with the front cover-section a guiding means, preferably in the form of studs or posts for properly centering the front cover-section upon the frame-section and help retain said front cover-section in place. Fig. 8 is an inner 85 face view of the one frame-section and longitudinal vertical section of the said front cover-section with the inlay removed, the said view representing the manner of securing the parts together; and Fig. 9 is a detail sectional representation of a portion of the said front 90 cover-section and one of the said guiding studs or posts. Fig. 10 is a detail transverse vertical section of the said front cover-section, showing a modified form of guiding stud 95 or post struck up from the metal body of the front cover-section; and Fig. 11 is a cross-section of one of the pivots or hinge connection between the two bag-frame sections and the front cover-section. 100

Similar characters of reference are employed in the above-described views to indicate corresponding parts.

In the said drawings the reference character 1 indicates the complete bag-frame, the same being of any desirable shape and configuration, and, as indicated in the accompanying drawings, the invention being prefer-

ably applied to that class of bag-frames which are used with chatelaine-bags and such other bags which are worn upon the body of a person. In these forms of bags and bag-frames the frame-section nearest the body of the person when worn is known as the "rear" or "back" frame-section, and in the accompanying drawings this frame-section is indicated by the reference character 2 and the other frame-section (indicated in the drawings by the reference character 3) is termed the "front" frame-section. These frame-sections 2 and 3 are of the usual right-angular cross-section, as shown in the several figures of the drawings, the said sections being provided at their respective ends with pintle-receiving ears or lugs 4 for the reception of suitable pins or rivets 5 for operatively connecting the two frame-sections in their pivoted or hinged relation. The said rear or back frame-section 2 is provided with the usual leather or other suitable covering 6 and has arranged against its inner face, as indicated in Fig. 6 of the drawings, the portion 7 of the mouth of the bag, the said portion 7 being secured in place by means of the inlay 8 and rivets or pins 9, substantially as shown, the rivet-heads 10 being exposed upon the back of the said leather-covered frame-section, as clearly illustrated in Figs. 2, 3, 4, and 6 of the drawings.

From an inspection of Figs. 6 and 7 it will be seen that the front bag-frame section 3 is free from any covering of leather or the like and has arranged against its inner face the portion 11 of the mouth of the bag, the said portion 11 being secured in place by means of an inlay 12 and rivets or pins 13, the rivet-heads 14 being arranged upon the outer face of the said frame-section 3. That the said rivet-heads 14 may be concealed from view at the front of the bag-frame, and thereby provide a neat and unobstructed front face, I have arranged upon and so as to cover the greater portion of the said frame-section 3 a front cover-section 15, which consists, preferably, of the right-angled portions 16 and 17, corresponding in cross-section to the cross-section of the said frame-section 3 and being provided at its end portions with pintle-receiving lugs or ears 18. The said front cover-section 15 has a suitable covering 19, of leather or other suitable material. The said front cover-section 15 is fitted directly upon the front frame-section 3, and its perforated ears or lugs 18 register with the pintle-receiving ears or lugs of the two frame-sections 2 and 3, the parts being operatively connected by means of the rivets 5, hereinabove mentioned. That the said front cover-section 15 may be properly secured in its operative position in the manner illustrated more particularly in Fig. 8 of the drawings each rivet 5 is made with a pair of holding-shanks 20, which when arranged in the perforated ears or lugs of the respective frame-sections

tions 2 and 3 and the front cover-section 15 are then bent over, as shown, and thereby prevent the separation of the parts, but still permit the hinged or pivotal relation of the two frame-sections, as will be clearly evident. It will be understood, however, that any other forms of pintles or pivot-rivets may be employed, if desired. In addition to this means of fastening the said front cover-section 15 upon the frame-section 3 the right-angled portion or member 16 of the front cover-section may be provided upon its inner face with one or more downwardly-extending holding lugs or posts 21, which act as guides for properly centering the cover-section 15 during the assembling of the parts and prevent any lateral displacement of the said front cover-section 15 by being fitted in depressions 22, formed by suitably-raised portions 23 in the edge portion 24 of the frame-section 3, as clearly illustrated in Figs. 4, 7, and 8 of the drawings. One manner of securing the said posts or lugs 21 upon the inner surface of the portion or member 16 of the front cover-section 15 is represented more particularly in Fig. 9 of the drawings, each post or lug 21 having a shank 25, which is placed in an opening 26 in the said portion or member 16 and then riveted down, as shown, that the edge portions 27 of the lug or post 21 will be forced tightly upon the inner surface of said portion or member 16 to provide a positive and operative construction. In lieu of the said posts or lugs 21 the portion or member 16 of the front cover-section 15 may be made with downwardly-extending lips or projections 27', which are struck out of the metal body of the front cover-section, the hole or opening 28 which is thus formed being covered over by the leather or other suitable covering 19 and the said lips or projections 27' serving as guide posts or lugs in the manner hereinabove described by being located against the marginal edge 24 of the bag-frame section 3 when the said front cover-section is arranged upon the said frame-section 3. The said front cover-section 15 is preferably provided with a suitably-shaped open part 29, and the said frame-section 3 has in its marginal edge portion 24 an open or cut-away part 30, the said open part 29 being located above the open part 30 and the said front cover-section 15 having secured upon its outer face and above the said open part 29 a suitable bag-fastener, as 31, with the holding mechanism of which can be brought in holding engagement a suitable holding-catch, as 32, when the catch 32 is made to enter the two openings 29 and 30 during the closing operation of the two frame-sections 2 and 3.

From the foregoing description of my invention it will be clearly understood that I have devised a simply-constructed bag-frame for use more especially with chatelaine-bags, the frame being provided with a rivet-

head-concealing means, preferably in the form of a front cover-section, behind which the rivet-heads are arranged, and thereby providing a frame the front face of which is not spoiled by the usual and unsightly rivet-heads used for securing the bag-frame to the mouth of the bag

5 Although I have described my invention in connection with the leather or other suitable coverings for the one frame-section and for the front cover-section, it will be clearly understood that such leather or other suitable coverings are not essential to the nature of my present invention and may be dispensed with, if desired.

10 Having thus described my invention, what I claim is—

1. In a bag-frame, the combination, with the hinged or pivoted main frame-sections, of a separate front cover-section conforming to and arranged upon the outer face of one of said main frame-sections, said cover-section serving as a rivet-head-concealing means, substantially as and for the purposes set forth.

2. In a bag-frame, the combination, with a pair of hinged or pivoted main frame-sections, of an independent front cover-section arranged upon the outer face of one of said frame-sections to conceal the rivet-heads by means of which the frame-section is attached to the mouth of a bag, and means for securing said front cover-section upon said main frame-section, substantially as and for the purposes set forth.

3. In a bag-frame, the combination, with a pair of hinged or pivoted main frame-sections, of an independent front cover-section arranged upon the outer face of one of said frame-sections to conceal the rivet-heads by means of which the frame-section is attached to the mouth of the bag, and centering devices connected with the said front cover-section and the bag-frame section upon which the said front cover-section is arranged to prevent lateral movement of said front cover-section upon the frame-section, substantially as and for the purposes set forth.

4. In a bag-frame, the combination, with a pair of hinged or pivoted bag-frame sections, of an independent front cover-section arranged upon one of said frame-sections to conceal the rivet-heads by means of which the frame-section is attached to the mouth of a bag, and centering devices connected with the said front cover-section and the bag-frame section upon which the said front cover-section is arranged to prevent lateral movement of said front cover-section upon the frame-section, consisting of downwardly-extending lugs on said front cover-section in engagement with portions of the said frame-section, substantially as and for the purposes set forth.

5. A bag-frame comprising a pair of main

frame-sections, each frame-section being provided with pintle-receiving lugs, an independent front cover-section upon the outer face of one of said frame-sections, pintle-receiving lugs connected with said front cover-section, 70 and connecting-pintles in the receiving-lugs of said front cover-section and said frame-sections, substantially as and for the purposes set forth.

6. A bag-frame comprising a pair of main frame-sections, each frame-section being provided with pintle-receiving lugs, an independent front cover-section upon the outer face of one of said frame-sections, pintle-receiving lugs connected with said front cover-section, 75 connecting-pintles in the receiving-lugs of said front cover-section and said frame-sections, and centering devices connected with the said front cover-section and the bag-frame section upon which said front cover-section is arranged to prevent lateral displacement of the said front cover-section upon said frame-section, substantially as and for the purposes set forth.

7. A bag-frame comprising a pair of frame-sections, each frame-section being provided with pintle-receiving lugs, an independent front cover-section upon one of said frame-sections, pintle-receiving lugs connected with said front cover-section, connecting-pintles 95 in the receiving-lugs of said front cover-section and said frame-sections, and centering devices connected with the said front cover-section and the bag-frame section upon which said front cover-section is arranged to 100 prevent lateral displacement of the said front cover-section upon said frame-section, consisting of downwardly-extending lugs on said front cover-section in engagement with portions of the said frame-section, substantially as and for the purposes set forth.

8. A bag-frame comprising a pair of hinged or pivoted main frame-sections, and a rivet-head-concealing cover-section arranged upon and separably and detachably connected 110 with the outer face of one of said frame-sections, substantially as and for the purposes set forth.

9. A bag-frame comprising a pair of hinged or pivoted main frame-sections, a holding-catch rigidly fixed upon one of said frame-sections, a rivet-head-concealing cover-section arranged upon and separably and detachably connected with the outer face of the other frame-section, and a bag-frame fastener fixed upon said front cover-section capable of receiving the holding-catch for locking the frame-sections in their closed relation, substantially as and for the purposes set forth.

10. A bag-frame comprising a pair of main frame-sections, each frame-section being provided with pintle-receiving lugs, an independent front cover-section conforming to and arranged upon the outer face of one of 130

said frame-sections, pintle-receiving lugs connected with said front cover-section, and pintles in the receiving-lugs of said front cover-section and said frame-sections, each 5 pintle comprising a pair of shanks having bent end portions, substantially as and for the purposes set forth.

11. A bag-frame comprising a pair of main frame-sections, each frame-section being provided with pintle-receiving lugs, an independent front cover-section conforming to and arranged upon the outer face of one of said frame-sections, pintle-receiving lugs connected with said front cover-section, and 10 pintles in the receiving-lugs of said front cover-section and said frame-sections, each pintle comprising a pair of shanks having bent end portions, all combined with centering devices connected with the said front 15 cover-section and the bag-frame section upon which the said cover-section is arranged to prevent lateral displacement of said front cover-section upon said frame-section, substantially as and for the purposes set forth.
12. A bag-frame comprising a pair of frame sections, each frame-section being provided with pintle-receiving lugs, an independent front cover-section upon one of said frame-sections, pintle-receiving lugs connected with 20 said front cover-section, and pintles in the 25
- 30

receiving-lugs of said front cover-section and said frame-sections, each pintle comprising a pair of shanks having bent end portions, all combined with centering devices connected with the said front cover-section and the bag-frame section upon which the said cover-section is arranged to prevent lateral displacement of said front cover-section upon said frame-section, consisting, of downwardly-extending lugs on said front cover-section in engagement with portions of the said frame-section, substantially as and for the purposes set forth. 35

13. A bag-frame comprising a pair of hinged or pivoted frame-sections, one of said frame-sections having receiving depressions in its marginal edge, a rivet-head-concealing cover-section upon said frame-section, and lugs upon said cover-section registering with the receiving depressions of said frame-section, substantially as and for the purposes set forth. 40

In testimony that I claim the invention set forth above I have hereunto set my hand this 11th day of July, 1904.

BENNO VOM EIGEN.
